UNITED STATES PATENT OFFICE.

CHARLES JACOBSON, OF WARREN, PENNSYLVANIA.

GAS-REGULATOR.

SPECIFICATION forming part of Letters Patent No. 662,938, dated December 4, 1900.

Application filed February 13, 1900. Serial No. 5,065. (No model.)

To all whom it may concern:

Be it known that I, CHARLES JACOBSON, of Warren, in the county of Warren and State of Pennsylvania, have invented certain new 5 and useful Improvements in Gas-Regulators, of which the following is a specification.

My invention has relation to gas-regulators, and has for its object certain improvements whereby the gas - pressure from wells and 10 mains can be reduced and regulated in a uniform and reliable manner, as will now be fully described, reference being had to the accompanying drawings, in which—

Figure 1 is a sectional elevation of a regulator constructed according to this invention 15 and having a balanced valve. Figs. 2 and 3 are similar views of modifications of the valve.

Referring to Fig. 1, A is the body of a regulator, and B the cover, having between them 20 the diaphragm C, to which is fastened the cup D by means of the screw K.

E is a rod passing through plug I and having a spring G pressing on its upper end, which is enlarged for that purpose.

25 H is a screw by which the pressure of the spring G on rod E can be adjusted. The lower end of rod E is in contact with the upper end of screw K and exerts a pressure on it, and consequently on the diaphragm C, depending 30 on the stiffness of spring G and the position of screw H. The part F, having the spring G, adjusting-screw H, and rod E, can be removed and the pressure on diaphragm C regulated by weights placed in the cup D.

35 J is an opening in the regulator-cover for the purpose of keeping atmospheric pressure on the top of the diaphragm C.

Fastened at one end to screw K and at the other end to the lever N is a lever L, ful- 40 crumed near the top of the standard M.

The lever N is provided with rollers at each end to allow for freedom of movement.

One end of lever N is kept in place by the projection O, and the opposite end operates 45 the valve T U by raising and lowering.

Valve T U is made up of two parts, each part having a seat. The upper part T is com- 50 posed of wings or guides and having a screw t formed at its top in the center, which screws into a flat disk X, having an eye or loop pro- jecting up for movably engaging one end of

lever N. Between the two parts of T is held a soft substance 1, like rubber, for a packing to make a perfect joint at the valve-seat. The lower part U is fastened to T by means of a 55 screw 4 and holds a packing 2, similar to 1. U is recessed on its under side to take the packing 2, which is held in place by washer 3 and screw 4. The gas entering at S presses equally up and down on valve T U, making 60 it balanced and easy to operate with high pressures. When the valve T U is raised, part of the gas goes directly up into the regulator past valve T, and part goes down past valve U and through passage R to the regu- 65 lator.

The outlet for the gas from the regulator is through the opening P.

It will appear from Fig. 1 and the foregoing description that when a pressure is ex- 70 ereted on the top of diaphragm C by means of the spring G or weights in cup D the valve T U will be opened through the opera- tion of levers N and L. When sufficient gas has entered the regulator to raise the dia- 75 phragm C against the pressure above it, the valve T U is forced down and the supply cut off. Upon the gas being drawn from the regulator through the opening P the diaphragm again falls and the valve T U is raised, re- 80 peating the cycle of operations.

Fig. 3 shows a modification of valve for high pressure to be used in place of T U when a balanced valve is not desirable. The opening for the gas is small and the seat is 85 at the bottom. The end of the lever simply rests on top of the valve, and when it is raised it does not raise the valve, as in Figs. 1 and 2, but the valve is raised by the gas- pressure below it.

90 Fig. 2 shows another modification of a valve for medium and light pressure and also a modification of guiding and seating the same.

Where valves shown in Figs. 1 and 2 are used, the gas can only enter the regulator 95 through them, as no passage R is used.

Having thus described my invention, what I claim as new therein, and desire to secure by Letters Patent, is—

1. In a gas-regulator, the combination with 100 a gas-chamber having an inlet and outlet and a diaphragm, of a valve controlling the inlet

of gas, a weight supported upon the diaphragm, a lever connected with the valve and having its opposite end fulcrumed, said lever having a roller bearing at each end, and a second lever connected with the diaphragm and having its opposite end connected with the first-named lever at a point between the opposite ends of the latter whereby the valve is opened by the depression of the diaphragm and is closed by gas-pressure upon said diaphragm.

2. In a gas-regulator, the combination of a gas-chamber, a controlling-valve and a diaphragm, of a lever having one end connected with the valve and the opposite end fulcrumed, rollers journaled in the ends of said lever, a standard or support, and a second lever connected at one end with the diaphragm, and fulcrumed to said standard or support, and having its opposite end pivotally connected with the first-named lever at a point between the ends of the latter, whereby the sinking of the diaphragm raises the valve to admit gas and the ascent of the diaphragm, by gas-pressure, closes said valve and cuts off the gas-supply.

3. In a gas-regulator, the body or case having a gas inlet and outlet, a valve having a loop or eye, and a weighted diaphragm, in combination with means for operating the valve consisting of a pair of connected levers one of which has its free end connected with the diaphragm and the other has its free end loosely and movably connected with the eye or loop of the valve and said first-named lever fulcrumed between its ends whereby the

weighted diaphragm opens the valve and gas-pressure closes it.

4. The combination with a gas-chamber, a diaphragm and a gas-controlling valve having a stem provided with an eye or loop, of a lever having a rolling connection with said eye or loop and having a rolling fulcrum at the opposite end, and a second lever fulcrumed between its ends, having one end connected with the diaphragm and the opposite end connected with the first-named lever at a point between the opposite ends of the latter.

5. The combination with a gas-chamber having an inlet and outlet and a valve-controlled passage from the inlet to the chamber, of a valve consisting of a body having wings forming gas-passages, a disk secured to the body and to seat within the gas-chamber to prevent the escape of gas through the said gas-passages said disk having an open eye or loop, a second disk separated from the lower side of the body whereby the lower ends of the gas-passages are normally open to receive gas from the main inlet, said lower disk seating upon and closing the entrance to the lower gas-passage, and means for operating the valve including a pair of levers one loosely and movably connected with said eye or loop and the other connected with the diaphragm and also connected with the first-named lever at a point between the ends of the latter.

CHARLES JACOBSON.
